(57) **CLAIM**

The ornamental design for an electric toothbrush handle, as shown and described.

DESCRIPTION

FIG. 1 is a front perspective view of an electric toothbrush handle according to a first embodiment of the new design; FIG. 2 is a rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a front perspective view of an electric toothbrush handle according to a second embodiment of the new design; FIG. 10 is a rear perspective view thereof; FIG. 11 is a front elevation view thereof; FIG. 12 is a rear elevation view thereof; FIG. 13 is a left side elevation view thereof; FIG. 14 is a right side elevation view thereof; FIG. 15 is a top plan view thereof; and, FIG. 16 is a bottom plan view thereof.

The broken lines in the drawings illustrate portions of the article that form no part of the claimed design.

1 Claim, 8 Drawing Sheets
